UNITED STATES PATENT OFFICE.

GEORGE SEIGFRIED BRUSH, OF ZANESVILLE, OHIO.

DESIGN FOR A JUG.

Application filed September 20, 1926. Serial No. 19,119. Term of patent 3½ years.

To all whom it may concern:

Be it known that I, GEORGE SEIGFRIED BRUSH, a citizen of the United States, residing at Zanesville, in the county of Muskingum and State of Ohio, have invented a new, original, and ornamental Design for a Jug, of which the following is a specification, reference being had to the accompanying drawing, forming part thereof.

Fig. 1 is a side elevation of the jug showing my new design;

Fig. 2 is a front elevation of the same;

Fig. 3 is a side elevation opposite to that taken in Fig. 1.

I claim:

The ornamental design for a jug as shown.

GEORGE SEIGFRIED BRUSH.
